ELECTRICAL COUPLING CIRCUITS

Christopher Dering Colchester, Sanderstead, and Arthur Tisso Starr, Chelmsford, England, assignors to Radio Corporation of America, a corporation of Delaware

Application November 5, 1940, Serial No. 364,430
In Great Britain August 31, 1939

8 Claims. (Cl. 178—44)

The present invention relates to coupling networks, and particularly to coupling networks for coupling two alternating current input circuits to a common output circuit.

According to the present invention a coupling circuit for coupling two alternating current input circuits of different frequencies to a common output circuit comprises an impedance network connected between one conductor of one input circuit and the corresponding one conductor of the other input circuit, a second impedance network connected between the other conductor of said one input circuit and the corresponding other conductor of the other said input circuit, and a resistance connected between said other conductor and the said corresponding one conductor, one conductor of the output circuit being connected to said one conductor of said one input circuit and the other conductor of the output circuit being connected to the said corresponding other conductor of said other input circuit, and wherein said first mentioned impedance network presents a high impedance to currents of the frequency of said one input circuit and a low impedance to currents of the frequency of said other input circuit and said second impedance network presents a high impedance to currents of the frequency of said second input and a low impedance to currents of the frequency of said one input circuit. The said resistance should preferably be equal to the impedance of the output termination.

Where it is desired to couple more than two input circuits to a common output circuit, the input circuits may be coupled to pairs in the manner above set forth, and the outputs of the several coupled pairs again coupled.

The invention is illustrated in the accompanying drawings wherein Fig. 1 shows the general circuit; Figs. 2 and 3 show the forms which networks Z and

impedance elements; Fig. 9 shows the reactance curves for elements Z and

$$\frac{R^2}{Z}$$

5 of Fig. 1, Fig. 10 shows the circuit of Fig. 1, Z and

$$\frac{R^2}{Z}$$

10 being replaced respectively by the networks of Figs. 2 and 3; Fig. 11 shows the circuit of Fig. 1, Z and

$$\frac{R^2}{Z}$$

15 being replaced respectively by the networks of Figs. 4 and 5; and Fig. 12 shows a circuit of the form of Fig. 1 but for coupling four input circuits to a common output circuit Z and

$$\frac{R^2}{Z}$$

being replaced respectively by the networks of Figs. 7 and 8.

20 In Fig. 1, the symbols I_1 and I_2 represent the two input circuits and Z represents the common output circuit. Z and

$$\frac{R^2}{Z}$$

25 represent the two impedance networks. The impedance of Z should, ideally, be infinite at the frequency

$$\frac{\omega_1}{2\pi}$$

30 of input circuit I_1 , and should be zero at the frequency

$$\frac{\omega_2}{2\pi}$$

35 of input circuit I_2 . The impedance

$$\frac{R^2}{Z}$$

40 should, ideally, be infinite at the frequency of input circuit I_2 , and should be zero at the frequency of input circuit I_1 . R represents a resistance connecting the input ends of Z and

$$\frac{R^2}{Z}$$

45 of Fig. 1 may take; Figs. 4 and 5 illustrate modifications of Figs. 2 and 3 to overcome the effect of dissipation in the resistive components of I_1 , I_2 and I_3 ; Fig. 6 shows the manner of coupling together more than two input circuits to a common output circuit; Figs. 7 and 8 show modified

The simplest form of Z is that in which Z is zero when ω is zero or has the value of ω_2 , and is infinite when ω has the value of ω_1 or is infinite as illustrated in Fig. 9 which shows the reactance curves for Z (full line) and

$$\frac{R^2}{Z}$$

(broken line).

The network Z may take the form, shown in Fig. 2, of an inductance L_1 shunted by a condenser C_3 , the whole being in series with a further inductance L_2 . The inverse network

$$\frac{R^2}{Z}$$

15

may take the form, shown in Fig. 3, of an inductance L_3 in series with a condenser C_1 , the whole being shunted by a condenser C_2 . This is shown in Fig. 10.

The impedance of the network Z is given by

$$Z = \frac{j\omega(L_1+L_2)\left(1-\omega^2\frac{L_1L_2C_3}{L_1+L_2}\right)}{1-\omega^2L_1C_3}$$

If, as stated, the frequency of input circuit I_1 is

$$\frac{\omega_1}{2\pi}$$

and that of input circuit I_2 is

$$\frac{\omega_2}{2\pi}$$

then where

$$\left. \begin{aligned} \omega^2 L_1 C_3 &= 1 \\ \frac{\omega^2 L_1 L_2 C_3}{L_1 + L_2} &= 1 \end{aligned} \right\} \quad (1)$$

$$Z = \frac{j\omega(L_1+L_2)\left(1-\frac{\omega^2}{\omega_3^2}\right)}{\left(1-\frac{\omega^2}{\omega_1^2}\right)} \quad (2)$$

It will be seen that there are two relations in Equations 1 to determine the three unknown quantities L_1 , L_2 , C_3 . A third relation is arbitrary, and the best choice is given by making the loss curves in the neighborhood of ω_1 and ω_2 of the same shape. If θ_1 is the transfer constant from input 1 to the output and θ_2 from input 2 to the output then

$$\left. \begin{aligned} \theta_1 &= 1 + \frac{R}{Z} \\ \theta_2 &= 1 + \frac{Z}{R} \end{aligned} \right\} \quad (3)$$

To obtain the same shape for the loss curves, it is necessary that

$$\left(\frac{d}{d\omega} \frac{R}{Z} \right)_{\omega_1} = \left(\frac{d}{d\omega} \frac{Z}{R} \right)_{\omega_2}$$

This gives

$$L_1 + L_2 = \frac{R\omega_2}{\omega_1^2} \quad (4)$$

Thus, for network Z Equations 1 and 4 give

$$\left. \begin{aligned} L_1 &= \frac{R}{\omega_1} \left(\frac{\omega_2 - \omega_1}{\omega_1 - \omega_2} \right) \\ L_2 &= \frac{R}{\omega_2} \\ C_3 &= \frac{1}{R\omega_1 \left(\frac{\omega_2 - \omega_1}{\omega_1 - \omega_2} \right)} \end{aligned} \right\} \quad (4)$$

and for the inverse network

$$\frac{R^2}{Z}$$

Equations 1 and 4 give

$$\left. \begin{aligned} C_1 &= \frac{1}{R\omega_1 \left(\frac{\omega_2 - \omega_1}{\omega_1 - \omega_2} \right)} \\ C_2 &= \frac{1}{\omega_2 R} \\ L_3 &= \frac{R}{\omega_1 \left(\frac{\omega_2 - \omega_1}{\omega_1 - \omega_2} \right)} \end{aligned} \right\} \quad (B)$$

Coils L_1 , L_2 , L_3 , have resistances R_1 , R_2 , R_3 (see Figs. 4 and 5) which, for the frequency ranges concerned, may be deemed to be constant. The primary effect of dissipation of energy in these resistances is to upset the balance of the networks with a resultant transference of energy from one input circuit to the other. This disadvantage may be overcome by connecting across condenser C_3 in the Z network a high resistance

$$\frac{R^2}{R_3}$$

and across condensers C_1 and C_2 in network

$$\frac{R^2}{Z}$$

high resistances

$$\frac{R_2}{R_1}$$

and

$$\frac{R^2}{R_2}$$

respectively. The circuit when thus modified is shown in Fig. 11.

Where it is desired to couple four input circuits of frequencies

$$\frac{\omega_1}{2\pi}, \frac{\omega_2}{2\pi}, \frac{\omega_3}{2\pi} \text{ and } \frac{\omega_4}{2\pi}$$

(these being in order of magnitude), to a common output circuit, this may be effected as illustrated in Fig. 6, by combining inputs I_1 and I_2 , and I_3 and I_4 respectively, and then combining the pairs. In this case the best pass frequency of the pair I_1 and I_2 may be between ω_1 and ω_2 , preferably nearer to ω_2 since the attenuation rises more steeply beyond ω_2 . The best pass frequency of the pair I_3 and I_4 may then be between ω_3 and ω_4 . The networks will be of the form described above in connection with Figs. 2 to 5. Similar conditions apply to combining the pairs. In this case the best pass frequency of the pair I_1 and I_2 may be between ω_1 and ω_2 , preferably nearer to ω_2 since the attenuation rises more steeply beyond ω_2 . The best pass frequency of the pair I_3 and I_4 may then be between ω_3 and ω_4 . The networks will be of the form described above in connection with Figs. 2 to 5. Similar conditions apply to the inputs I_3 and I_4 . The corresponding loss curves are shown in Fig. 9.

It is preferred, however, to group alternative channels in pairs such that the impedance Z of the drawing has, in this case, to be infinite at ω_1 and ω_3 and zero at ω_2 and ω_4 . In this case the network Z may take the form, shown in Fig. 7,

of an inductance L_3 shunted by a condenser C_5 , and inductance L_4 shunted by a condenser C_4 and an inductance L_5 , these three elements being connected in series. The inverse network

$$\frac{R^2}{Z}$$

may take the form, shown in Fig. 8, of an inductance L_4 in series with a condenser C_2 , an inductance L_5 in series with a condenser C_3 and a condenser C_1 these three elements being connected in parallel. The circuit according to this modification is shown in Fig. 12. The values of the several inductances and condensers are given by

$$\left. \begin{aligned} L_1 &= \frac{R}{\omega_2} \left[\sqrt{\frac{(\omega_3^2 - \omega_1^2)(\omega_5^2 - \omega_1^2)}{(\omega_4^2 - \omega_1^2)(\omega_4^2 - \omega_5^2)}} \right] \\ L_2 &= L_1 \left[\frac{(\omega_3^2 - \omega_1^2)(\omega_4^2 - \omega_1^2)}{\omega_1^2(\omega_3^2 - \omega_4^2)} \right] \\ L_3 &= L_1 \left[\frac{(\omega_4^2 - \omega_3^2)(\omega_5^2 - \omega_3^2)}{\omega_3^2(\omega_4^2 - \omega_5^2)} \right] \\ C_4 &= \left[\frac{1}{\omega_1^2 L_2} \right] \\ C_5 &= \left[\frac{1}{\omega_3^2 L_3} \right] \\ L_4 &= C_4 R^2 \\ L_5 &= C_5 R^2 \\ C_1 &= \frac{L_1}{R^2} \\ C_2 &= \frac{L_2}{R^2} \\ C_3 &= \frac{L_3}{R^2} \end{aligned} \right\} \quad \begin{aligned} (C) \\ (D) \end{aligned}$$

The invention is susceptible of various modifications; thus for example the impedance networks Z and

$$\frac{R^2}{Z}$$

may take any of the forms which give the same impedances as those given in Figs. 4, 5, 7 and 8, and which may be derived by known methods from Equations A, B, C, and D. Other networks giving equally good results to those given by Equations C and D, and derived by making cyclic changes of ω_1 , ω_2 , ω_3 , and ω_4 may be used.

Although the arrangement in which the product of the values of impedances Z and

$$\frac{R^2}{Z}$$

is equal to R^2 (R being the value of the resistance connected to the two impedances and being equal to the output impedance) gives best results, matters may be so arranged that R^2 is equal to the product of R and of the impedance of the output circuit.

What is claimed is:

1. A coupling circuit for coupling two alternating current input circuits of different frequencies to a common output circuit, comprising an impedance network connected between one conductor of one input circuit and the corresponding one conductor of the other input circuit, a second impedance network connected between the other conductor of said one input circuit and the corresponding other conductor of the other said input

circuit, and a resistance connected between said other conductor and the said corresponding one conductor, one conductor of the output circuit being connected said one conductor of said one input circuit, the other conductor of the output circuit being connected to the said corresponding other conductor of said other input circuit, said first mentioned impedance network being comprised of an inductance shunted by a condenser,

10 the whole being in series with a further inductance and presenting a high impedance to currents of the frequency of said one input circuit and a low impedance to currents of the frequency of said other input circuit, said second impedance network being comprised of an inductance in series with a condenser, the whole being shunted by a condenser and having a high impedance to currents of the frequency of said second input and a low impedance to currents of the frequency 20 of said one input circuit.

2. A coupling circuit for coupling two alternating current input circuits of different frequencies to a common output circuit, comprising a first impedance network, a resistance and a second

25 impedance network serially connected in the order named between the two conductors of the output circuit, the series connection of one of the impedance networks and the resistance being connected between the terminals of one input circuit, the series connection of the other of said impedance networks and the resistance being connected between the terminals of the other input circuit, said networks each consisting of inductance and capacitance and each presenting a

30 high impedance to currents of the frequency of the input circuit between the terminals of which it is connected and a low impedance to currents of the frequency of the input circuit between the terminals of which it is not connected.

3. A coupling circuit for coupling two alternating current input circuits of frequency ω_1 and ω_2 respectively to a common output circuit, comprising a first impedance network, a resistance and a second impedance network serially connected in the order named between the two conductors of the output circuit, the conductors of the input circuit of frequency ω_1 being connected across the series connection of the first impedance network and the resistance, the conductors of the input circuit of frequency ω_2 being connected across the series connection of the second impedance network and the resistance, said networks each consisting of inductance and capacitance, the first presenting a high impedance to

45 currents of frequency ω_1 and a low impedance to currents of frequency ω_2 and the second presenting a high impedance to currents of frequency ω_2 and a low impedance to currents of frequency ω_1 .

50 4. A coupling circuit according to the invention defined in claim 3 wherein the first impedance network comprises a pair of inductances in series and a capacity in shunt to one of them, and the second impedance network comprises the series connection of an inductance and a capacity and a capacity in shunt to said series connection.

55 5. A coupling circuit according to the invention defined in claim 3 wherein the first impedance network comprises a pair of inductances L_1 and L_2 in series and a capacity C_3 in shunt to inductance L_1 , and the second impedance network comprises the series connection of an inductance L_4 and a capacity C_1 and a capacity C_2 in shunt to said series connection, the values of

said inductances and capacities being determined by the following expressions:

$$L_1 = \frac{R}{\omega_1 \left(\frac{\omega_2 - \omega_1}{\omega_1 - \omega_2} \right)} C_1 = C_2 = \frac{1}{R \omega_1 \left(\frac{\omega_2 - \omega_1}{\omega_1 - \omega_2} \right)}$$

$$L_3 = \frac{R}{\omega_1 \left(\frac{\omega_2 - \omega_1}{\omega_1 - \omega_2} \right)}$$

$$L_2 = \frac{R}{\omega_2} \quad C_2 = \frac{1}{\omega_2 R}$$

R being the value of the resistance serially connecting the impedance networks.

6. A coupling circuit according to the invention defined in claim 3 wherein the first impedance network comprises a pair of inductances in series and a capacity in shunt to one of them, and the second impedance network comprises the series connection of an inductance and a capacity and a capacity in shunt to said series connection, and a resistance connected across each of the condensers in said impedance networks.

7. A coupling circuit according to the invention defined in claim 3 wherein the first impedance network comprises a pair of inductances L_1 and L_2 in series and a capacity C_3 in shunt to inductance L_1 , and the second impedance network comprises the series connection of an inductance L_3 and a capacity C_1 and a capacity C_2 in shunt to said series connection, and a resistance connected across each of the condensers

C_1 , C_2 and C_3 , the values of the resistances connected across the condensers C_1 , C_2 and C_3 being equal respectively to

$$\frac{R^2}{R_1}, \frac{R^2}{R_2} \text{ and } \frac{R^2}{R_3}$$

where R_1 , R_2 and R_3 are respectively the values of the resistive components of the inductances L_1 , L_2 and L_3 and R is the value of the resistance serially connecting the impedance networks.

10 8. A coupling circuit for coupling four alternating current input circuits of frequency ω_1 , ω_2 , ω_3 and ω_4 respectively to a common output circuit, comprising a first impedance network, a resistance and a second impedance network serially connected in the order named between the two conductors of the output circuit, the conductors of the input circuits of frequencies ω_1 and ω_3 being connected across the series connection of the first impedance network and the resistance, the conductors of the input circuits of frequencies ω_2 and ω_4 being connected across the series connection of the second impedance network and the resistance, the first impedance network comprising three inductances in series and a capacity individually connected in shunt to two of them, and the second impedance network comprising the parallel connection of a capacity and two paths each consisting of a series connection of an inductance and a capacity.
